(Model.)

W. W. & F. P. PURSEL.
LATCH AND LOCK COMBINED.

No. 405,050.

Patented June 11, 1889.

UNITED STATES PATENT OFFICE.

WILLIAM W. PURSEL AND FRANK P. PURSEL, OF BERWICK, COLUMBIA COUNTY, PENNSYLVANIA.

LATCH AND LOCK COMBINED.

SPECIFICATION forming part of Letters Patent No. 405,050, dated June 11, 1889.

Application filed March 29, 1888. Serial No. 268,825. (Model.)

To all whom it may concern:

Be it known that we, WILLIAM W. PURSEL and FRANK P. PURSEL, citizens of the United States, residing at Berwick, in the county of 5 Columbia and State of Pennsylvania, have invented new and useful Improvements in Latches and Locks Combined, of which the following is a specification.

Our invention relates to improvements in 10 locks; and it has for its object to provide improved means for connecting and disconnecting the outside and inside knobs.

The invention consists in a certain novel 15 construction and combination of devices, fully set forth hereinafter in connection with the accompanying drawings, wherein—

Figure 1 is a perspective view of the lock. Fig. 2 is a front view with the face-plate removed. Fig. 3 is a horizontal sectional view 20 of the lock on the line $x x$ of Fig. 2. Fig. 4 is a detail sectional view of the knob-shaft, taken longitudinally. Fig. 5 is a detail view of the key.

Referring by letter to the drawings, A designates the case of the lock. B designates the 25 sliding bolted mounted therein. C designates a spring bearing against a shoulder b on the bolt and normally holding it extended, and D designates a cross-head at the rear end of the 30 bolt. A tumbler E is mounted in the case in front of the said cross-head, whereby when it is rotated one of its ends bears against the cross-head and retracts the bolt, and the barrel F of the tumbler is tubular, and is provided in one side with a longitudinal slot G. The bolt is provided near its front end with a socket H, which aligns with an aperture I in the side of the lock when the bolt is extended, and a spring-latch K is attached to 35 the side of the lock, and is provided with a pin k , which projects through the said aperture and engages the socket to hold the bolt in its extended position.

L represents a tubular knob-shaft, which is 40 mounted at its inner end in the barrel of the tumbler, and is provided on one side with a rib M, which engages the longitudinal slot 45 therein and enables the tumbler to be rotated by the shaft. A knob N is attached to the outer end of the shaft L, and a shoulder n is formed in the interior of the shaft a short distance from its outer end.

A knob-shaft O is mounted in the tubular shaft, and is provided at one end with a head o, which engages the shoulder n and prevents 55 the shafts from being drawn apart, but allows independent rotation thereof. This shaft O is provided on one side with a longitudinal groove or notch P, which is adapted to be aligned with an aperture S in the side of the 60 tubular shaft, and a spring-latch R is mounted on the side of the tubular shaft, and is provided with a pin r , which projects through the said aperture and engages the groove or notch, thereby locking the shafts together for 65 simultaneous operation. The outer end of the shaft O is squared to enable the knob Q to be secured thereon.

When the latch R is in its engaging position, it rests in a longitudinal groove s in the 70 side of the tubular shaft, and a sliding ring or handle T is mounted on the said latch, and is adapted to be moved from one end to the other of the same. When the said ring or handle is located at the free end of the latch, 75 it fits in a transverse groove s' in the side of the tubular shaft, and therefore allows the pin r to engage the groove or notch in the inner shaft; but when the ring or handle is drawn outward toward the other end of the 80 latch it raises the same out of the said longitudinal groove s and withdraws the pin r out of engagement with the groove or notch in the inner shaft.

U represents the ward of a key, which is 85 mounted permanently in the case in such a position that when turned it will engage one end of the cross-head on the bolt and retract the latter. This ward is provided with the short post V, which projects slightly beyond 90 the side of the case, and is provided with a longitudinal groove W, and when it is desired to operate the ward a key having a tubular shank provided in one side with a longitudinal rib or a stud is engaged over the 95 said post in such a manner that the said rib or stud will engage the groove in the latter.

The operation of the improved lock is as follows: The knob having the tubular shaft attached thereto is placed on the inside of the 100 door, and as it operates directly on the bolt the door may be opened at any time from the inside, but can only be opened from the outside when the interior shaft is locked to the

tubular shaft. The means for so locking the said shafts together are mounted on the tubular shaft, and therefore the improved lock performs the additional function of a dead-latch.

It will be seen that knob-shafts thus connected may be applied to any ordinary lock, so that their usefulness is not confined to the lock herein described.

10 The spring hereinbefore mentioned is peculiarly adapted to actuate the bolt promptly without much strain on the spring. The spring is of such a length as to reach from one side of the lock-case to the other, and it bears at its ends against the front side of studs or shoulders *e e* at the sides of the case. Thus the full length of the spring is free to be bent, and the bolt is provided with a rounded shoulder *b*, (above mentioned,) which bears 15 against the center of the said spring.

The principal reason for the frequent breakage of springs in locks of this character is, that they are ordinarily short and are bent abruptly; but in the improved lock the spring 20 is very long, and consequently the bend is gradual and comparatively slight.

Having thus described the invention, what we claim, and desire to secure by Letters Patent of the United States, is—

25 1. In a lock, the combination of the tubular shaft connected to the tumbler, the shaft *O*,

mounted in the tubular shaft and having a groove or notch in its side adapted to be aligned with an aperture in the tubular shaft, the spring-latch mounted on the tubular shaft 35 and engaging the said aperture and groove or notch, and the sliding ring or handle *T*, mounted on the latch, all constructed, arranged, and operated substantially as and for the purpose specified.

2. In a lock, the combination, with the tumbler having a barrel provided with a groove, of the tubular shaft mounted in the said barrel and having a rib *M* on its side engaging the said groove, the removable knob on the 45 end of the shaft, the knob-shaft *O*, mounted in the tubular shaft and having a head *o* engaging a shoulder *n* in the tubular shaft, the knob attached to the shaft *O*, and the spring-latch *R*, mounted on the tubular shaft and 50 adapted, when in its normal position, to lock the said shafts together, substantially as specified.

In testimony that we claim the foregoing as our own we have hereto affixed our signatures 55 in presence of two witnesses.

WILLIAM W. PURSEL.
FRANK P. PURSEL.
